DEVICE FOR CLAMPING TOGETHER PIECES OF SHEET MATERIAL TO FACILITATE RIVETING AND THE LIKE OPERATIONS

Alliott Verdon-Roe, Southampton, England, as-
signor to Aviation Developments Limited,
London, England, a joint-stock company of
England

Application May 10, 1938, Serial No. 207,172
In Great Britain May 14, 1937

6 Claims. (Cl. 85—9)

The present invention refers to improved de-
vices for clamping together pieces of sheet ma-
terial, especially to facilitate riveting and the like
operations.

5 When light metal sheets have to be riveted to-
gether the hitherto usual practice is to use ordi-
nary bolts and nuts for securing the sheets to-
gether and much time is lost in threading the
10 nuts on the bolts, especially in the case of closed
structures such as the hull of a flying boat or
the fuselage or wing of an aeroplane of the kind
having a metal skin. In such an operation a
second person is usually required to thread the
15 nuts on the bolts and the operation frequently
presents great difficulty, e. g., in awkwardly
placed corners, and in some cases the inside end
of the bolt may be completely inaccessible. The
present invention affords a means by which one
20 person can quickly clamp sheets together using
only one hand and without the aid of any tools.

The improved device according to the present
invention comprises an internally threaded tubu-
25 lar member, a claw member externally threaded
for engagement with the internally threaded
tubular member and an apertured abutment
member, through which the claw member passes,
being slidably and non-rotatable therein, and
25 which is rotatably and non-slidably retained on
one end of the tubular member.

30 Preferably the abutment member is provided
with a central projecting spigot (adapted to enter
an aperture in the workpieces), said spigot being
apertured to allow the claw member to pass
through it.

35 By relatively rotating the tubular member and
the abutment member the claw member is ex-
tended or is withdrawn from the abutment mem-
ber according to the direction of rotation. In
40 using the device the abutment and tubular mem-
bers are rotated until the claw is extended to a
distance depending on the number and thickness
of sheets to be riveted together. The claw is
then inserted in a hole passing through all the
45 sheets until its claw end is clear of the inner
face of the inner sheet. The abutment member
being against the outer face of the outer sheet,
the tubular member is screwed in the direction
50 to withdraw the claw and cause it to engage the
inner sheet; further rotation of the tubular mem-
ber causes all the sheets to be clamped together.

The provision of a spigot on the outer face of
the abutment member ensures that the device is
sufficiently centralised with respect to the hole in
the sheets to prevent the claw end from slipping
55 back through the hole when the claw member is
retracted to tighten the device.

In a preferred form of construction the shank
of the claw member is flat and passes through a
slot in the abutment member to prevent relative
60 movement of these parts.

Preferably also one end of the internally
threaded tubular member is outwardly flanged
and is embraced by the abutment member which
is cup-shaped and has its free edge loosely closed
in over the flanged end of the tubular member 5

It is further advantageous to provide the abut-
ment member with a ring of rubber or a like
yieldable frictional substance for abutment on
the workpiece. Such a yieldable ring grips the 10
face of the workpiece without damaging the same
and prevents the abutment member from turn-
ing when the screwed tubular member is rotated
within it. Alternatively the rubber or like ring
15 may be omitted and the end of the abutment
member may be roughened to afford a frictional
grip on the workpiece and prevent the abutment
member from turning. In this case however care
must be taken not to clamp the device too tightly
20 or the surface of the workpiece will be marked
by the abutment member.

The present invention and a manner of per-
forming the same will be more fully understood
from the following description of an embodiment
of the invention having reference to the accom-
panying drawing, in which:

Fig. 1 is a view in elevation of the device as-
sembled.

Fig. 2 is an "exploded" view of the same, in
side elevation, partly in section, the parts being 30
separated from one another.

Fig. 3 is a sectional view taken along the line
3—3 of Fig. 1.

Fig. 4 is a plan view of the showing of Fig. 1.

Referring to the drawing:

A tubular member 5 internally threaded at 6
is provided with a flange 7 presenting a shoulder
8 where it joins the main body of the member,
which is of lesser diameter. The claw member
comprises an externally threaded part 10 en- 40
gagable in the thread 6 of the tubular part 5
and a flattened shank 11 terminating in a claw
12. The abutment member is of cup-shaped
form comprising a disc 13 and a skirt 14. In
the centre of the face of the disc part 13 is a 45
spigot 15 and a slot 16 is formed through the
spigot and the disc part 13 so that the spigot
is constituted by two half-round parts as shown
in Fig. 4. The device is assembled by inserting
the shank 11 of the claw member through the 50
slot 16 of the abutment member which is then
seated on the end of the tubular member 5 so
that the skirt 14 of the abutment member sur-
rounds the flange 7. The free edge 14b of the
skirt 14 is then spun or pressed in over the shoul- 55
der 8 of the flange 7 so as to retain the abutment
member on the tubular member. The edge 14b
must of course not be pressed in so tightly as to
prevent free rotation of the tubular member in
the abutment member and to assist this the 60

shoulder 8 should be formed with a generous radius.

It may be noted that the slot 16 must be long enough to allow the shank 11 of the claw member to pass through it. If the slot 16 is located centrally of the abutment member and the claw 12 extends slightly to one side as shown, the tip of the claw 12 will overlap the end of the slot 16 when the claw member is withdrawn into the barrel of the tubular member, thus limiting the inward movement of the claw member and preventing it from being lost by being screwed out of the other end of the tubular member.

To enable the abutment member to obtain a good grip on the surface of the sheet against which it abuts an annular groove is formed in the disc part 13 of the abutment member and in this groove is inserted a rubber ring 17. In the embodiment illustrated the rubber ring 17 is of trapezoidal section, the base being wider than the top part so that it is firmly retained in the annular groove. This however is not essential and a ring of rectangular section may be employed as an alternative.

25 Alternatively again, as hereinbefore stated, the rubber ring 17 may be omitted and the face of the disc part 13 milled or otherwise roughened to enable the required frictional grip to be obtained.

30 For convenience in manipulating the device the skirt 14 of the abutment member is knurled as shown at 14a and the end 9 of the tubular member is also knurled as shown in Fig. 1.

For the sake of cheapness of production the 35 claw member may if desired be entirely pressed out of sheet metal, in which case the part 10 will not present a continuous thread but two opposed sets of teeth, which after the first pressing operation resemble the teeth of a saw, being given the required angle to cooperate with the thread 8 of the tubular member by a second pressing operation performed in a die.

In using the device as illustrated the spigot 15 is inserted in a hole drilled through the sheets 45 to be clamped so that the claw 12 enters the hole. The abutment member is then held up against the outer sheet and the tubular member 5 rotated by means of the knurled end 9 until the claw 12 engages behind the innermost sheet. 50 The knurled end 9 is then rotated in the opposite direction until the sheets are gripped firmly between the claw 12 and the rubber ring 17 of the abutment member. The sheets are now firmly held together and the operator has both hands free for riveting or drilling further holes 55 or such like operations.

What I claim is:

1. A device for clamping together pieces of sheet material, for example to facilitate riveting, 60 including an internally threaded tubular member, a claw member externally threaded for engagement with the internally threaded tubular member and an apertured abutment member, through which the claw member passes being 65 slidable and non-rotatable therein, and which is rotatably and non-slidably retained on one end of the tubular member and is provided with a central projecting spigot (adapted to enter an aperture in the workpieces), said spigot being apertured to allow the claw member to pass 70 through it.

2. A device for clamping together pieces of

sheet material, for example to facilitate riveting, including an internally threaded tubular member, an abutment member rotatably and non-slidably retained on one end thereof and having a slot 5 therein, and a claw member having a part externally threaded for engagement with the internally threaded tubular member and a flat part traversing the slot of said abutment member, being slidable but non-rotatable in said slot and terminating in a claw.

3. A device for clamping together sheet material, for example to facilitate riveting, comprising an internally threaded tubular member, a claw member having a hook-like claw at one end, an externally threaded part for engagement with the internal thread of the tubular member and having a non-circular shank between the claw and the threaded part, and an abutment member swivelably secured to the tubular member and having a slot through which passes the shank of the claw member, said slot engaging the shank to prevent relative rotation between the claw and the abutment members.

4. A device for clamping together sheet material, for example to facilitate riveting, comprising an internally threaded tubular member outwardly flanged at one end, a claw member having a hook-like claw at one end, an externally threaded part for engagement with the internal thread of the tubular member and having a non-circular shank between the claw and the threaded part, and a cup shaped abutment member having a slot through which passes the shank of the claw member, said slot engaging the shank to prevent relative rotation between the claw member and the abutment member which latter fits loosely over the flanged end of the tubular member, its free edge being closed in over said flanged end to retain it swivelably thereon.

5. A device for clamping together sheet material, for example to facilitate riveting, comprising an internally threaded tubular member, a claw member having a hook-like claw at one end, an externally threaded part for engagement with the internal thread of the tubular member and having a non-circular shank between the claw and the threaded part, and an abutment member swivelably secured to the tubular member and having a slot through which passes the shank of the claw member, said slot engaging the shank to prevent relative rotation between the claw and abutment members and a ring of yielding friction material carried by said abutment member to make contact with a workpiece.

6. A device for clamping together sheet material, for example to facilitate riveting, comprising an internally threaded tubular member, a claw member having a hook-like claw at one end, an externally threaded part for engagement with the internal thread of the tubular member and having a non-circular shank between the claw and the threaded part, an abutment member swivelably secured to the tubular member and having a slot through which passes the shank of the claw member, said slot engaging the shank to prevent relative rotation between the claw and the abutment members and a spigot, adapted to enter an aperture in the workpieces, mounted on the abutment member and apertured to allow the claw member to pass through it.

ALLIOTT VERDON-ROE.
